TUMBLING MILL

Otto E. Zahn, Mishawaka, Ind., assignor to
 American Foundry Equipment Company,
 Mishawaka, Ind., a corporation of Delaware

Application July 14, 1938, Serial No. 219,127

16 Claims. (Cl. 51-9)

This invention relates to tumbling mills for cleaning and smoothing castings, forgings and the like.

In cleaning, polishing, hardening or otherwise treating metal articles such as castings, forgings and the like, the process may be carried out in a tumbling mill in which the articles are placed and subjected to the action of projected abrasive particles while the articles are being tumbled.

When a single tumbling barrel is used it has been the usual practice to charge the articles to be treated into the barrel when the supply of projecting abrasive is shut off. After charging the barrel, the abrasive may be projected on to and against articles therein with sufficient impact to clean the articles such as castings while they are being tumbled. After they have been treated the requisite length of time, the discharge of the treated castings requires shutting off the abrasive supply while the tumbling barrel is being unloaded and again loaded with more castings.

It is, therefore, desirable to avoid these shut downs and to maintain the abrasive projecting mechanism in operation continuously whereby to do active work without the necessity of relatively long shut downs incident to charging and discharging the tumbling barrel operating on the so-called batch system.

The present invention accomplishes the foregoing desirable end by providing a frame or carrier adapted to be rotated, the frame or carrier serving to support a plurality of tumbling barrels or pockets which are arranged to be brought in and out of the path of a stream of abrasive projected at blasting velocities. Provision is made to charge the barrels with objects to be treated at a predetermined position while objects in barrels in the path of projected abrasive are receiving treatment. At the same time barrels containing objects which have been treated may be discharged at another predetermined position. Consequently, the treatment which ordinarily, although not always, consists in a cleaning or blasting operation, may be substantially continuous and the time incident to charging and discharging is not utilized at the expense of shutting down the abrasive projecting mechanism.

According to one form of the invention, the apparatus, which for convenience is herein referred to as a mill, may comprise a master frame generally circular in form adapted to be rotatably driven on suitable supports about a vertical axis of rotation. A plurality of rotatable shafts with sprockets thereon may be mounted for rotation in journals in the frame, it being preferable to

have these main sprocket shafts radially disposed from the aforementioned axis of rotation of the frame. Discs forming inner barrel heads may be suitably mounted in the master frame between consecutive main sprocket shafts for rotation; the axis of rotation of the shafts carrying these inner barrel head discs being also preferably radially disposed with reference to the axis of rotation of the frame and in the same horizontal plane as the axes of rotation of the main sprocket shafts.

A conveyor may be trained over the sprockets and under the inner barrel heads on suitable guides whereby to form a plurality of pockets. Means are provided to cause the conveyor to travel linearly in a generally circumferential path about the axis of rotation of the master frame thus to provide a tumbling action to objects in the pockets.

To form the outer end walls of the pockets, rotatable discs may be mounted on shafts suitably journaled in frames, one for each pocket. These discs may be adapted to form outer barrel heads and the frames carrying them may be positioned opposite the inner barrel heads to form with the conveyor and inner barrel heads a plurality of tumbling barrels. Provision is made to raise or lower these frames thus to permit objects in the barrels to be removed with facility.

The master frame assembly thus generally described may be mounted on suitable wheels riding on circular tracks and may be caused to rotate bodily, step by step, if desired, about a common axis. A suitable abrasive projecting mechanism may be mounted adjacent to the path of travel of the tumbling barrels and positioned to throw abrasive on to objects to be treated in the tumbling barrels.

As hereinbefore indicated, the master frame, being designed for step by step rotation permits of charging the barrels mounted thereon at a predetermined position or station while simultaneously articles are being cleaned or treated at another station or stations while, at the same time cleaned or treated articles may be discharged at still another station.

In addition to the apparatus described generally in the foregoing, means are provided to collect abrasive which has been discharged into the tumbling barrels and return it to be recycled, if desired.

Although the novel features which are believed to be characteristic of this invention will be particularly pointed out in the claims appended here-to, the invention itself, as to its objects and ad-

vantages, and the manner in which it may be carried out, may be better understood by referring to the following description taken in connection with the accompanying drawings forming a part thereof, in which

Fig. 1 is a view in elevation of the tumbling mill;

Fig. 2 is a top plan view partly broken away;

Fig. 3 is a view on line 3-3 of Fig. 2;

Fig. 4 is a view on line 4-4 of Fig. 2;

Fig. 5 is a view of the lower side of a section of the conveyor;

Fig. 6 is a view developed in a flat plane on line 6-6 of Fig. 2.

In the following description and in the claims, various details will be identified by specific names for convenience, but they are intended to be as generic in their application as the art will permit. Like reference characters denote like parts in the several figures of the drawings.

The master frame assembly represented generally by the reference character 10 comprises an inner wall 11 substantially circular in shape, supported on a circular channel member 12 which also may support vertically extending channels 13 held in spaced relation by members 14 extending from said vertical channels to said inner walls 11. The frame 10 is carried on wheels 15 journaled in circular channel members 12 and 16. A plurality of such wheels 15 ride on a circular track 17 supported on I beams 18 mounted on a suitable foundation 19. A sprocket chain 20 is mounted on a sprocket 21 extending around the frame 10 and driven by small sprocket wheel 22 mounted on a shaft 9 in turn driven by a belt 8 on a shaft 7 having a gear 6 engaging a gear 5 driven by an electric motor 4. Thus the frame may be caused to rotate on the circular track 17 about a vertical axis.

Mounted radially with respect to the axis of rotation of the frame 10 are a plurality of sprocket shafts 23 and 24. The inner ends of shafts 23 are mounted in suitable journals 25 in the inner wall 11 of the frame 10. The outer ends of the shafts 23 are mounted for rotation in journals 26 supported on cross members 27 fixed to the vertical channels 13. The sprocket shafts 24 are also mounted for rotation in the frame 10, the outer ends of shafts 24 being mounted in journals 28 supported in the same manner as journals 26. It will be noted, however, that the inner ends of shafts 24 differ from shafts 23 in that they extend inwardly and have affixed thereto a worm wheel 29 which engages a worm 30 mounted to rotate in a journal 31 in turn mounted in a bracket 32 carried on the inner wall 11. Worm drive 30 is connected through a speed reducer 33 (see Fig. 4) and driven by sprocket wheel 34 and sprocket chain 35 driven by a motor 36.

There are three such sprocket shafts 24 connected by worm gear mechanism as just described. Each worm shaft has a sprocket wheel 37 mounted thereon and a sprocket chain 38 engages them. Consequently when the motor 36 is driven, sprocket chain 35 drives sprocket wheel 34 and in turn through the speed reducer 33 the worm 30 is driven which also drives the three wheels 37, thus causing sprocket shafts 24 to rotate in their respective journals.

Sprocket shafts 23 and 24 each have keyed thereon a pair of sprocket wheels 39 and 40. Inner sprockets 39 are smaller in diameter than outer sprockets 40. Trained over these sprocket

wheels 39 and 40 is an endless conveyor 41 to be described more in detail hereinafter.

Alternately with the sprocket shaft journals in the inner wall 11 are mounted journals 42. These journals 42 carry short shafts 43 for rotation therein to which are fixed inner barrel head members 44. Mounted for rotation on frames 45 are outer barrel head members 46. The barrel heads 46 are fixed to short shafts 47 mounted for rotation in journals 48 which are in turn mounted on the frames 45. Also mounted on frames 45 are guide wheels 49 riding in channels 13. The frames 45, therefore, are movable vertically to bring the barrel heads 46 opposite barrel heads 44 and when the frames are lowered the barrel heads in turn are lowered away from a position opposite its complementary inner barrel head 44.

It will be observed that there is a frame 45 carrying an outer barrel head for each of the inner barrel heads 44. Each outer barrel head frame or carrier 45 has a guide wheel 50 which rides in a track 51 mounted on the vertical casting wall 52 which encloses the master frame 10.

A semicircular channel guide track segment 53 carried on brackets 54 mounted on the vertical channel members 13 of the master frame 10 is mounted adjacent each of the barrel head carrier frames 45. As will be described herein-after in connection with the conveyor 41, these guide segments are adapted to assist in causing the conveyor to form with the conveyor and barrel heads a plurality of radially disposed and, at the same time circumferentially arranged, tumbling barrels of generally truncated conical shape.

The endless conveyor 41 comprises a series of radially disposed spaced apart bars 55 connected together at their inner ends by links 56 and 57 fixed to the bars. The links are connected by shafts carrying bearing wheels 59. Similar links 60 and 61 connect the outer ends of the bars. The shafts 62 connecting the links 60 and 61, in addition to carrying bearing wheels 62, also carry guide wheels 63 which ride in channel segments 53.

The endless conveyor 41 is trained over the upper half of the sprockets 39 and 40 and under the inner barrel heads 44. The outer margin of the conveyor is trained to ride with the semicircular segments 53. By reason of the guide wheels 63 riding in the channels and the inner margin of the conveyor being trained under the rotatable inner barrel heads 44, the conveyor is adapted to form a plurality of radially disposed pockets (see Figs. 3 and 6). When the outer barrel head carrier 45 is raised in the position shown in Fig. 3 there is formed a tumbling barrel. Six such barrels are shown but it is within the contemplation of the invention to have more or less.

It will now be apparent from the foregoing description that the conveyor may be driven linearly and in a generally circumferential path. Hence, objects in the pockets will be given a tumbling action. Bearing wheels riding in the sprocket grooves 64 of sprocket 40 on the driven sprocket shafts 24 will effect this movement. Furthermore the master frame may be caused to rotate about its vertical axis in a step by step movement. The step by step movement may be effectuated by known means such as a time switch 3 in the electrical circuit connecting the motor 4. For convenience of description six

stations I to VI inclusive are indicated on the drawings (see Fig. 2).

Mounted over the pockets at stations III and IV on the top wall 65 of the casing designated 5 generally by the reference character 66 are abrasive projecting mechanisms which may be of the centrifugal throwing type. These abrasive throwing wheels 67 may be mounted on a cantilever 68 pivoted on a support 69 mounted on 10 the casing. A lug 70 extending from the lever 68 carries a guide wheel 71 riding in a channel 72 fixed to the master frame 10. This channel guide track at each tumbling barrel has a valley portion 73. Hence it will be observed that as each 15 pocket passes the abrasive projecting stations III and IV the throwing wheel is lowered through openings 74 in the casing top wall 65. As the master frame 10 rotates the wheel may be lifted so as not to interfere with the movement of the 20 frame. A guide slot 75 is provided in the casing which permits the shaft of the throwing wheel 67 to be lifted with the wheel. The abrasive throwing wheel may be driven by a motor 76 and belt 77.

25 There is provided in the casing 52 a charging port 78 and a discharging port 79. These are shown as being at stations I and VI respectively. The guide track 51 extending around the inside of the casing wall 52 is dipped at station VI. 30 Consequently, when the frame is rotated the frames 45 carrying the outer barrel heads 46 are lowered away from the tumbling pockets formed by the conveyor when at that station (see Fig. 6). As the frame 10 is further rotated 35 the outer barrel head carrying frame 45 is raised as shown at station I (see Fig. 6) by reason of the guide wheel 50 travelling in the channel track 51. The frame remains raised until it again reaches station VI, at the discharging port 79.

40 An abrasive collecting and recycling mechanism is provided which comprises a collection trough 80 in the bottom of the bottom wall 81 of the casing. The collected abrasive may be raised through an elevation conduit 82 and returned to the abrasive charging chamber 83 from 45 which the abrasive may be fed to the abrasive throwing wheels as desired through charging conduits 84 and 85.

The mill may be operated as follows: The various motors are caused to operate. While the 50 frame 10 dwells by reason of its step by step rotation, castings are charged at charging port 78, station I. Meantime castings which have been charged to the tumbling barrels previously will be subjected to abrasive treatment at stations III 55 and IV. When they have been given treatment for a predetermined length of time, the frame will rotate another step and the empty tumbling barrel will reach a position opposite the charging port 78, station I. Finally as barrels containing 60 treated castings reach station VI, at the discharge port 79, the frame 45 will have been caused to move downwardly by reason of the dip (see Fig. 4) in the guide track 51. This moves 65 the outer barrel head away from the end of the pocket leaving it open and the treated castings therein will be automatically discharged out of the discharging port 79 since the moving conveyor will cause them to be tumbling. The outer margin of the conveyor being lower results in 70 the castings being forced out.

75 It will be observed that the mill described in the foregoing, may be operated continuously. As castings are being charged at one station, castings are being treated at another station or

other stations and simultaneously treated castings are being discharged from the mill.

While certain novel features of the invention have been disclosed herein, and are pointed out in the annexed claims, it will be understood that 5 various omissions, substitutions and changes may be made by those skilled in the art without departing from the spirit of the invention.

What is claimed is:

1. In apparatus of the character described, a 10 carrier mounted to rotate about an axis, an inner barrel head mounted on said carrier, an outer barrel head opposite said first mentioned barrel head, a link conveyor adjacent said barrel heads and trained to form with said heads a tumbling 15 barrel the axis of which is substantially radial to the axis of rotation of said carrier, and means to cause said tumbling barrel to move with said carrier in an arc about the axis of rotation of 20 said carrier.

2. In apparatus of the character described, a carrier mounted to rotate about an axis, a barrel head mounted on said carrier, a vertically movable frame opposite said first mentioned barrel head, a barrel head mounted on said frame, a 25 link conveyor adjacent said barrel heads and trained to form with said heads a tumbling barrel the axis of which is substantially radial to the axis of rotation of said carrier, means to rotate said carrier to cause said tumbling barrel to move 30 in an arc about the axis of rotation of said carrier.

3. In apparatus of the character described, a carrier mounted to rotate about an axis, an inner barrel head mounted on said carrier, an outer barrel head opposite said first mentioned barrel head, an endless conveyor adjacent said barrel heads and trained to form with said heads a tumbling barrel the axis of which is substantially radial to the axis of rotation of said carrier, 40 means to rotate said carrier to revolve said tumbling barrel in an orbit about the axis of rotation of said carrier and means to cause said conveyor to travel linearly and tumble articles in said barrel.

4. In apparatus of the character described, a carrier mounted to rotate about an axis, a rotatable barrel head mounted on said carrier, a vertically movable frame mounted on said carrier opposite said first mentioned barrel head, 50 a rotatable barrel head mounted on said frame, an endless link conveyor adjacent said barrel heads and adapted to form with said heads a tumbling barrel, means to rotate said carrier to cause said tumbling barrel to travel in an orbit about the axis of rotation of said carrier, means to cause said conveyor to move linearly to tumble articles in said barrel and abrasive projecting mechanism mounted to project abrasive on to articles in said barrel.

5. In apparatus of the character described, a frame mounted to rotate about a substantially vertical axis, means mounted on said frame carrying barrel ends, means mounting a conveyor, said conveyor being trained to form a plurality 65 of tumbling barrels having their axes disposed substantially radially with reference to the axis of rotation of said frame, means to rotate said frame about its axis of rotation, and means to cause said conveyor to travel linearly to tumble 70 objects in said barrels.

6. In apparatus of the character described, a master frame mounted to rotate about a substantially vertical axis, means mounted on said master frame carrying barrel ends, means mount- 75

- ing a conveyor, said conveyor being trained to travel in a generally circumferential path and to form a plurality of tumbling barrels having their axes disposed substantially radially with reference to the axis of rotation of said frame, means to rotate said frame about its axis of rotation, and means to cause said conveyor to travel linearly and in said generally circumferential path to tumble objects in said barrels.
7. A tumbling mill which comprises a master frame mounted to rotate about a substantially vertical axis, means mounted on said frame carrying inner barrel heads, vertically movable means carrying outer barrel heads, means mounting a conveyor, said conveyor being trained to travel in a generally circumferential path and to form with said heads a plurality of tumbling barrels having their axes disposed substantially radially with reference to the axis of rotation of said frame, means to rotate said frame about its axis of rotation, and means to cause said conveyor to travel linearly to tumble objects in said barrels.
8. A tumbling mill including a tumbling barrel comprising a section of an endless link conveyor trained to form a curvilinear pocket, means to rotate said conveyor linearly to tumble articles in said pocket, a barrel head to close one end of said pocket, a second barrel head for the opposite end of said pocket, said second mentioned barrel head being movable to close said opposite end whereby to retain articles in said barrel during treatment thereof and to open said opposite end to automatically discharge articles from said pocket by the linear movement of said conveyor.
9. A tumbling mill comprising a rotatable frame, a plurality of tumbling barrels of substantially truncated conical shape radially disposed on said frame, the side walls of said barrels consisting of a continuous link conveyor movable linearly to provide a tumbling action to objects in said barrels, means for guiding said conveyor in a generally circumferential path and to form said side walls, means including driven sprockets to drive said conveyor linearly, means to rotate said frame whereby to cause said barrels to travel in an orbit about its axis of rotation, rotatable heads providing a closure for the inner ends of said barrels and heads movable toward and away from the outer ends of said barrels to provide a closure for said outer ends.
10. A tumbling mill comprising a generally circular master frame mounted to rotate about a vertical axis, a continuous link conveyor, means to train said conveyor to travel in a generally circumferential path about said axis and to form a plurality of pockets, inner barrel heads mounted for rotation in said frame to close the inner ends of said pockets, a plurality of frames mounted for vertical movement on said master frame, outer barrel heads mounted for rotation in said second mentioned frames to close the outer ends of said pockets, said heads and conveyor forming a plurality of tumbling barrels rotatable in an orbit about the axis of rotation of said master frame, and abrasive projecting mechanism to project abrasive on to articles in said barrels in their orbit of travel.
11. A tumbling mill comprising a generally circular casing, a master frame in said casing, a circular track mounted to carry said frame in said casing about a vertical axis, a continuous link conveyor, means including sprocket wheels and
- tracks to train said conveyor to travel in a generally circumferential path and to form a plurality of pockets, inner barrel heads mounted for rotation in said frame to close the inner ends of said pockets, a plurality of outer barrel heads carrying frames mounted for vertical movement, channels to guide said frames in their upward and downward movements, outer barrel heads mounted for rotation in said second mentioned frames to close the outer ends of said pockets, a guide track on said casing to raise and lower said barrel head carrying frames, said heads and conveyor forming a plurality of tumbling barrels when said barrel carrying frames are in their upper position, abrasive projecting mechanism to project abrasive on to articles in said barrels.
12. A tumbling mill comprising a generally circular casing, a master frame in said casing, a circular track mounted to carry said frame in said casing about a vertical axis, a continuous link conveyor, means including sprocket wheels and tracks to train said conveyor to travel in a generally circumferential path and to form a plurality of pockets, inner barrel heads mounted for rotation in said frame to close the inner ends of said pockets, a plurality of outer barrel heads carrying frames mounted for vertical movement, channels to guide said frames in their upward and downward movements, outer barrel heads mounted for rotation in said second mentioned frames to close the outer ends of said pockets, a guide track on said casing to raise and lower said barrel head carrying frames, said heads and conveyor forming a plurality of tumbling barrels when said barrel carrying frames are in their upper position, abrasive projecting mechanism to project abrasive on to articles in said barrels.
13. A tumbling mill comprising a generally circular master frame mounted to rotate about a vertical axis, a continuous link conveyor, means including sprocket wheels to train said conveyor to travel in a generally circumferential path and to form a plurality of pockets, inner barrel heads mounted for rotation in said frame to close the inner ends of said pockets, a plurality of frames mounted for vertical movement on said master frame, outer barrel heads mounted for rotation in said second mentioned frames to close the outer ends of said pockets, said heads and conveyor forming a plurality of tumbling barrels rotatable in an orbit about the axis of rotation of said master frame, means to rotate said sprockets to cause said conveyor to travel linearly whereby to tumble articles in said barrels and abrasive projecting mechanism to project abrasive on to articles in said barrels in their orbit of travel.
14. A tumbling mill comprising casing, a generally circular master frame mounted to rotate in said casing about a vertical axis, a continuous link conveyor, means to train said conveyor to travel in a generally circumferential path and to form a plurality of pockets on said frame, inner barrel heads mounted for rotation in said frame to close the inner ends of said pockets, a plurality of outer barrel head carrying frames mounted for vertical movement on said master frame within said casing, outer barrel heads mounted for rotation in said outer barrel head carrying frames to close the outer ends of said pockets, said heads and conveyor forming a plurality of tumbling barrels rotatable in an orbit about the axis of rotation of said master frame, a track mounted on said casing

to raise said barrel head carrying frames during a part of the rotation of said master frame and to lower said barrel head carrying frame during another part of the rotation of said master frame 5 and abrasive projecting mechanism to project abrasive on to articles in said barrels during a part of their orbit of travel.

15. A tumbling mill comprising a rotatable frame, an endless link conveyor, means to train 10 said conveyor to form a plurality of radially disposed substantially truncated conical shaped pockets, a plurality of inner barrel heads rotatable on said frame and adapted to close the inner ends of said pockets, a plurality of outer barrel heads mounted for rotation in vertically movable 15 carriers for the outer ends of said pockets, means to drive said conveyor linearly to tumble articles in said pockets, means to revolve said pockets in an orbit about the axis of rotation of said 20 frame, means to move said carrier vertically to bring said outer barrel heads over the outer ends of said pockets during a part of their travel in said orbit and to remove said barrel heads from

said outer ends during a part of their travel in said orbit.

16. A tumbling mill comprising a rotatable frame, an endless link conveyor, means to train 5 said conveyor to form a plurality of radially disposed substantially truncated conical shaped pockets, a plurality of inner barrel heads rotatable on said frame and adapted to close the inner ends of said pockets, a plurality of outer barrel heads mounted for rotation in vertically movable 10 carriers for the outer ends of said pockets, means to drive said conveyor linearly to tumble articles in said pockets, means to revolve said pockets in an orbit about the axis of rotation of said frame, means to move said carrier vertically 15 to bring said outer barrel heads over the outer ends of said pockets during a part of their travel in said orbit and to remove said barrel heads from said outer ends during a part of their travel in said orbit and abrasive projecting means adapted 20 to project abrasive on to articles in said pockets.

OTTO E. ZAHN.
